UNITED STATES PATENT OFFICE.

THOMAS C. BRETT, OF RED OAK, IOWA.

TRAIN-PIPE COUPLING.

944,941.

Specification of Letters Patent. Patented Dec. 28, 1909.

Application filed September 21, 1909. Serial No. 518,757.

To all whom it may concern:

Be it known that I, THOMAS C. BRETT, a citizen of the United States, residing at Red Oak, in the county of Montgomery 5 and State of Iowa, have invented new and useful Improvements in Train-Pipe Couplings, of which the following is a specification.

The purpose of the present invention is 10 the provision of novel means for connecting the air pipes of railway cars so as to insure the setting of the brakes when required.

The invention is designed to provide coupling means which are automatic in action 15 both in establishing communication between the train pipes of cars when run together and in shutting off said train pipes when the cars are uncoupled thereby preventing the escape or waste of air.

20 The invention also has for its object to devise a coupling which is wholly automatic in action, connecting the train pipes and establishing communication between them when the cars are coupled and automatically 25 separating and closing the train pipes when the cars are uncoupled.

The invention consists of the novel features, details of construction and combination of parts, which hereinafter will be more 30 particularly set forth, illustrated in the accompanying drawings and pointed out in the appended claims.

Referring to the drawings forming a part 35 of the specification:—Figure 1 is a top plan view of a train pipe coupling embodying the invention, one set of coupling elements being in longitudinal section. Fig. 2 is a central longitudinal section of one coupling member. Fig. 3 is a detail view of the universal joint between the coupling member 40 and train pipe. Fig. 4 is a sectional view on the line 4—4 of Fig. 2. Fig. 5 is a detail section on the line 5—5 of Fig. 1. Fig. 6 is a sectional view of a modification.

45 Corresponding and like parts are referred to in the following description and indicated in all the views of the drawings by the same reference characters.

In accordance with this invention each 50 end of a car is similarly equipped with a coupling member whereby when two cars are run together the complementary coupling members engage and connect the train pipes. The coupling members may be of any desired 55 construction and secured to the platform or bed timbers of railway cars in any

substantial way. Each coupling member comprises a sleeve 1 closed at its inner end as shown at 2 and having a socket 3 at its outer end, said socket being formed as a segment 60 of a sphere. A connecting piece 4 is provided at one side of the sleeve 1 and has a chamber 5 which flares outwardly from the sleeve 1. An opening 6 establishes communication between the smaller end of the chamber 5 and sleeve 1. A sleeve 7 is provided and arranged parallel with the sleeve 1 and is connected thereto by the intermediate part 4. The sleeve 7 is provided at opposite ends with packing glands 8 which insure the formation 70 of close joints between the said sleeve and a pipe or tube 9 constituting the main body of the coupling member. The pipe or tube 9 is slidably mounted in the sleeve 7 and is normally pressed forward by 75 means of a spring 10 mounted upon the pipe 9 and confined between a shoulder thereof and a bearing in which said pipe is mounted. An opening 11 is formed in a side of the pipe or tube 9 and communicates with the 80 chamber 5. Portions of the tube or pipe 9 are contracted to form inner valve seats 12 and 13 with which valves 14 and 15 co-operate. An opening 16 is provided in a side of the pipe or tube 9 and extends 85 through the seat 13. Both valves 14 and 15 are mounted upon a rod or stem 17 which is arranged to move within the pipe or tube 9. The valves 14 and 15 are of like formation and are hollow as indicated most clearly in 90 Figs. 4 and 5 to admit of the passage of air or other fluid through them. The stem or rod 17 may consist of a rod or pipe and the valves 14 and 15 may be secured thereto in any manner. It is preferred, as indicated 95 most clearly in Fig. 5 to have the stem or rod 17 connected to the valves by means of screw thread joints.

A coupling head is provided upon the outer end of the pipe or tube 9 and consists 100 of a sleeve 18 tapered at its outer end as shown at 19 and provided at its inner or rear end with an enlargement 20 of a size and shape to snugly fit within the socket 3, said enlargement 20 having its outer surface 105 covered with rubber 21 or other packing material to insure the formation of a tight joint between the socket 3 and enlargement 20 when complementary coupling members are run together. The outer tapered end 19 of 110 the sleeve 18 is provided upon its inner side with a threaded opening to receive the

threaded end of the stem or rod 17 whereby the several parts 17, 18 and the valves 14 and 15 move together. A spring 22 located in the forward end of the sleeve 18 normally exerts a forward pressure upon the sleeve 18 to force the stem or rod 17 and the valves 14 and 15 forward whereby the outlet openings 11 and 16 are normally closed when the coupling is out of action. A disk 23 is mounted upon the stem or rod 17 and obtains a bearing against the front end of the pipe or tube 9 and serves to receive the end thrust of the spring 22. A packing gland 24 is fitted into a recess formed in the rear end of the enlargement 20 and insures the formation of a tight joint between the parts 18 and 9 so as to prevent escape of air.

The train pipe is indicated at 25 in Fig. 3 and is provided at one end with a coupling member 26 of ball shape. The inner end of the pipe or tube 9 is provided with a coupling member 27 of approximately spherical or ball form to receive the ball member 26 whereby a universal joint is provided between the two parts 9 and 25. In order to admit of the ready and convenient assembling of the parts one of the members as 27 is formed in sections, the sections being bolted or secured in any manner and adapted to have a packing ring between them to coöperate with the ball member 26 forming a tight joint while at the same time admitting of the pipes 9 and 25 having free play whereby the cars may be moved without producing injury to the connecting parts co-operating with the train or air pipes of the brake system. The member 26 has openings 31 for the passage of the air.

The sleeves 1 and 7 of the coupling member applied to each end of a car lie side by side and are so arranged that the sleeve 7 upon the end of one car comes opposite to the sleeve 1 of the coupling member upon the adjacent end of the car to be coupled. When the cars are run together the tapered end 19 of the head 18 of one car enters the socket or flared portion 3 of the coupling member upon the other car and as the cars come together the coupling head 18 is pressed inward against the tension of the spring 22 thereby moving the stem or rod 17 inward and carrying the valves 14 and 15 therewith so as to uncover the openings 11 and 16 thereby permitting the air to pass from one column to the other. The sleeve 18 is also provided with an outlet opening 28 whereby communication is established between the several parts when assembled. When the members of the train pipe coupling are assembled they are held in coöperative relation by the coupling means connecting the cars, the spring 22 of each being compressed as indicated in Fig. 1. When the cars are uncoupled the spring 22 of each train pipe coupling expands and moves the

sleeve 18 outward carrying the stem or rod 17 therewith and moving the valves 14 and 15 so as to cover the outlet openings 11 and 16.

It will be understood that the foregoing taken in connection with the accompanying drawings that the invention provides a train pipe coupling for railway cars which is wholly automatic in action both in coupling and uncoupling and in opening and closing the openings by means of which communication is established between the coupling members. It is also observed that the train pipe coupling herein disclosed will not interfere with the effective operation of the ordinary couplings for connecting the train pipes of railway cars.

In the modification shown in Fig. 6 the pipe 9 is provided with a cap 29 which is connected therewith by means of a screw threaded joint. The outer end of the cap 29 is reduced and provided with a stuffing box 30 through which the rod 17 passes. The spring 22 is mounted upon the reduced end of the cap 29.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative and that such changes may be made when desired as are within the scope of the claims appended hereto.

Having thus described the invention what is claimed as new is:—

1. In a train pipe coupling, the combination of a hollow member provided with lateral outlets, valves arranged within the hollow member for closing the outlets thereof and connected for simultaneous longitudinal movement, a movable coupling head having connection with said valves for movement therewith, means for normally holding the valves closed, and the coupling head advanced.

2. A train pipe coupling comprising a hollow member having portions in its length contracted to form inner valve seats having lateral outlets, valves arranged to operate in said pipe to close the outlets thereof, a stem connecting said valves, and a spring-actuated coupling head having connection with said stem to move therewith after unseating the valves and disclosing the openings of the valve seats.

3. In a train pipe coupling, the combination of a sleeve, a pipe mounted in said sleeve and adapted to move longitudinally, and having outlets in its sides, valves arranged

within the pipe for closing the outlets in the sides thereof, means connecting the valves, a coupling head slidably mounted upon said pipe and movable independently thereof, 5 and connecting means between the said valves and coupling head whereby the valves and coupling head move in unison.

4. In a train pipe coupling, the combination of a sleeve having a flared socket at one 10 end, a second sleeve spaced from and parallel with the first sleeve, a connection between the two sleeves having a chamber in communication with each, a pipe slidably mounted in the second sleeve and provided 15 in its sides with outlets, connected valves arranged within the pipe to close the outlets thereof, a coupling head mounted upon said pipe and having its outer end tapered and its inner end enlarged to fit the said socket 20 at the outer end of the first-named sleeve, said coupling head having the valves connected therewith, and a spring for normally pressing the coupling head outward.

5. In a train pipe coupling, and in combination with the coupling member, a train pipe, a universal joint between the coupling member and train pipe comprising ball shaped members, the inner ball shaped member having openings in its sides to establish 30 communication between the two members.

6. In a train pipe coupling and in combination with a coupling member, and a train pipe, a universal joint between the two, the 35 same comprising coöoperating ball shaped

members, the inner member having openings in its sides, and the outer member comprising sections which are adapted to be connected, and having a packing clamp between them to secure a close joint between 40 the two members.

7. A train pipe coupling comprising similar members, each member comprising a sleeve closed at its inner end, and provided at its outer end with a socket, a second 45 sleeve spaced from and parallel with the first-named sleeve, a connecting piece between the two sleeves having a chamber which flares toward said second sleeve, a pipe slidably mounted on the second sleeve, 50 and having outlet openings in its sides, and having tapered valve seats, valves arranged within the said pipe normally closing the outlets thereof, a stem connecting the valves, a coupling head slidably mounted upon the 55 pipe and having its outer end tapered and its inner end enlarged to correspond to the socket provided at the outer end of the first-mentioned sleeve, said coupling head having an opening in its side and having the stem 60 connecting the valves attached thereto, and springs arranged to exert an outward or forward pressure upon the said pipe and coupling head.

In testimony whereof I affix my signature 65 in presence of two witnesses.

THOMAS C. BRETT.
